Primary Examiner—Cathron C Brooks*Assistant Examiner*—Kevin K Rudzinski(74) *Attorney, Agent, or Firm*—Muncy, Geissler, Olds & Lowe, PLLC(57) **CLAIM**

The ornamental design for a data input and cursor control device, as shown and described.

DESCRIPTION

FIG. 1 is a right side elevational view of a data input and cursor control device showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right side elevational view of a date input and cursor control device showing my new design;

FIG. 8 is a left side elevational view thereof;

FIG. 9 is a front elevational view thereof;

FIG. 10 is a rear elevational view thereof;

FIG. 11 is a top plan view thereof; and,

FIG. 12 is a bottom view thereof.

The broken lines shown are included for the purpose of illustrating environmental structure and form no part of the claimed design.
